UNITED STATES PATENT OFFICE.

JOHN J. EDWARDS, OF ANN ARBOR, MICHIGAN.

INTERLEAVING MECHANISM.

Application filed March 6, 1922. Serial No. 541,267.

To all whom it may concern:

Be it known that I, JOHN J. EDWARDS, residing at Ann Arbor, in the county of Washtenaw and State of Michigan, a citizen of 5 the United States, have invented certain new and useful Improvements in Interleaving Mechanism, of which the following is a specification.

The object of this invention is to provide 10 simple, compact and efficient means for inserting absorbing or blotter sheets between printed sheets as the latter are delivered from a duplicating mechanism, thereby avoiding smearing of the freshly-printed 15 sheet and offsetting of the impression from one printed sheet to the back of a superposed printed sheet. Various devices have been heretofore suggested for accomplishing the stated result but none has been satisfactory in all respects, some being costly to install and necessitating more or less rebuilding of the duplicating mechanism or the supporting framework for the same while others could not be operated with any speed 20 or efficiency. My invention provides an interleaving apparatus which may be easily applied to any duplicating mechanism at a very low cost and may be operated efficiently at the same speed as the duplicating mechanism. The invention is especially applicable to machines embodying a rotary drum upon which a stencil is secured to make a printing impression upon a sheet fed past the drum by the rotation of the latter, although it may be used in connection with 35 other forms of duplicating mechanism.

In the accompanying drawings,

Figure 1 is a side elevation of an apparatus embodying my invention.

Figure 2 is a plan view of the same.

Figure 3 is an end elevation.

Figure 4 is a transverse section on the line 4—4 of Figure 1.

Figure 5 is a longitudinal section, the vertically movable support for the sheets being omitted.

Figure 6 is an enlarged longitudinal section of the means acting directly on the blotter or interleaving sheets.

Figure 7 is an enlarged detail section showing the means for securing and adjusting the support for the printed and interleaved sheets.

I have illustrated a duplicating mechanism comprising a supporting frame 1 in which is mounted a duplicating or stencil

drum or cylinder 2 which may be driven by a motor 3 through suitable gearing, as shown in Figure 1, or may be directly rotated through a hand crank 4, as shown in Figure 2. The printed sheets are delivered into a receptacle 5 which will preferably be provided with a vertically movable bottom 51. If the delivered sheet is required to drop a considerable distance it has a tendency to buckle and fold instead of lying flat on the platform or bottom 51. I, therefore, provide means whereby the platform may be secured at a comparatively high point when the work is started and may be lowered as the pile of printed and interleaved sheets increases. Upon one side of the receptacle, I secure a bracket 52 which is also secured to the upper end of a post or leg 53, the side of the receptacle being constructed with a vertical notch or open-ended slot 54 alined with the post. The platform 51 is carried upon the guide arms 55, 56 which extend through and play in the slot 54 and are provided at their ends with eyes 57, 58 encircling the post 53 whereby to guide the movement of the platform. It will be readily noted that the end portion 59 of the lower guide arm 56 is carried downwardly so that the guiding eyes 57 and 58 will be separated to produce an extended guiding engagement with the post and reduce the liability of the platform to sway. The post 53 is provided with a plurality of sockets or notches 60 in its front side and a latch pin 61 plays through the portion 59 of the lower guide arm to engage any one of said notches or sockets and thereby secure the platform at a desired height. The latch pin is carried by a latching lever 62 which is loosely mounted on a pin or screw 63 inserted through the lever into the guide arms and the platform, the inner or front terminal of the lever being offset from the guide arms to form a handle 64. When the top of the pile of sheets delivered onto the platform reaches the top of the receptacle, pressure is applied manually to the handle 64 of the latching lever to withdraw the pin 61 from the socket in which it is engaged whereupon the platform may descend. When the platform has been lowered sufficiently, the pressure on the handle 64 is released and the latch pin 61 engaged in another socket 60, as will be readily understood.

At the rear of the receptacle 5 and spaced

somewhat from the upper edge thereof, a feeding roll 6 is mounted in the supporting frame of the machine, the journal at one end of said roll being extended beyond the side 5 of the frame and equipped with a pulley 7 around which is trained a belt 8 which is also trained around a pulley 9 on the axis of the drum or cylinder 2 whereby the roll will be rotated with the drum. In operation, 10 the interleaving absorbent or blotter sheets 10 are fed over the roll 6 to be deposited in the receptacle 5, and they are held in close frictional contact with the feeding roll, so as to be moved forward by the rotation of 15 the roll, by a pressure roll 11 rotatably mounted in a bracket 12 which is fitted upon a rod 13 and secured in a set position thereon by a set screw 14 secured in the bracket and bearing upon the rod as shown and 20 as will be readily understood. The rod 13 has a pivotal movement at its ends in the supporting frame and, at one end, is constructed with a pendent crank 15 to which and to some fixed member is secured a spring 25 16 which tends constantly to swing the bracket 12 downwardly and thereby hold the pressure roll to the feed roll. The spring 16 may, of course, be attached to any stationary object and is shown attached to one 30 of a pair of bearing arms or brackets 17 depending from the sides of a magazine, tray or feed table 18 upon which the sheets 10 are piled. The magazine is secured to the main supporting frame and projects rearwardly therefrom, the rolls 6 and 11 being located immediately in advance of the magazine. As shown clearly in Figure 6, the interleaving sheets 10 are piled in the magazine with their lower or front ends immediately adjacent the bight presented by the 35 rolls 6 and 11. To cause the top sheet to enter the bight and be engaged by the rolls, I provide a feeder finger or pusher 19 which bears upon the sheets and may have its working face covered with rubber or other friction-creating material, indicated at 20, and the surface of the roll 6 may be of like material. The pusher or feeder finger 19 is split at its upper end, as at 21, to be engaged about a transverse carrier rod or bar 22 and secured thereon by clamping plates 23 and bolts 24, the bolts being inserted through the pusher above and below the carrier and the clamping plates serving also 40 to secure the friction cover 20 in place. The carrier rod 22 is supported by rocking arms 25 which are journaled in the bearing plates or brackets 17 and may be connected, as at 26. One end of the carrier 22 is bent downward, as at 27, and on said downturned arm is adjustably secured a weight 28 which holds the carrier rod and the pusher in such position that the pusher will bear upon the sheets 10. To permit the pusher to be raised 45 so that additional sheets may be placed in

the tray or magazine, a handle 29 is provided upon that rocking arm 25 adjacent the weighted arm 27 while from the arm 25 at the opposite side of the machine a pin 30 projects laterally to engage a notch 31 in the lower end of a block 32 which is carried by a pitman 33, said pitman 33 extending downwardly and forwardly and having its front end pivoted to a crank head 34 which is rotated from the main driving pulley 9 75 through intermediate gearing, as will be readily understood. By this arrangement, rotation of the crank head 34 will effect reciprocation of the pitman which, in turn will cause oscillation of the arms 25 so that the pusher will be moved forward and back over the pile of sheets. By securing the end of the pitman at the proper point in the length of the crank 34, the stroke of the pitman will be timed so that the pusher will feed the blotter sheets forward to the feed rollers at the proper intervals to interleave the printed sheets, it being understood that the feed rollers will engage a sheet whenever it may be fed forward to them. 90

In rear of the pusher, a stop and holder is provided to prevent backward movement of the top sheet when the pusher is returning to its normal position after having fed a sheet to the feed and presser rolls. This device comprises a transverse arm 35 pivotally mounted at its outer end upon a post 36 of any convenient form fixed upon the tray or magazine, and a weight 37 carried by the arm and of a weight proportionate 100 to the weight and quality of the paper or board used. On the front side of the weight, at the lower edge thereof, is a stop or gage plate 38 which rests upon the top interleaving sheet slightly in advance of the rear end 105 thereof, as shown in Figure 6.

The interleaving or blotter sheets do not pass from the feed roll 6 directly into the receptacle 5 but are supported temporarily above the receptacle while a printed sheet is 110 delivered thereto. The temporary support consists of a pair of fingers 39 projecting forwardly over the rear wall of the receptacle and having their rear portions 40 extending down in rear of the receptacle and secured radially in rock shafts 41 which are journaled in bearings provided therefor on the main frame and the rear end of the receptacle. As shown in Figures 3 and 4, a link 42 is pivoted at one end to the rear portion 40 of one of the fingers 39 above the fulcrum of the same while the opposite end of said link is pivoted to the inner end of a push rod 43 disposed below the fulcrums or rock shafts 41. The end of the push rod is also pivoted to a crank 44 depending from the rock shaft 41 at that same side of the machine, the result of the arrangement being that when the push bar 45 is actuated the fingers will be simultane- 115

ously rocked in opposite directions. The parts are held in normal positions by a spring 45 which is secured at its opposite ends to the push rod and to the member 5 40 more remote from the crank 44, respectively. When the push rod is forced inwardly, the fingers are swung toward each other to assume the positions shown in dotted lines in Figure 2 to receive and support the blotter sheet; the spring 45 will also be put under increased tension so that when the pressure on the push rod is released the spring will at once contract and the fingers will be rocked outwardly, the 10 sheet dropping between them into the receptacle. The outer end of the push rod is pivoted to a crank pin 46 projecting radially from a vertically disposed rock shaft 47 mounted in a bracket 48 secured on the 20 side of the main frame. Near the upper end of the rock shaft 47, a crank pin 49 projects therefrom, and a tappet or striker 50 is secured to and depends from the pitman 33 and is adapted to impinge upon the 25 pin 49 which is held in the path of the tappet through the influence of the spring 45.

The operation will be readily understood. At each revolution of the printing or duplicating drum, a sheet is printed and fed from under the drum into the receptacle, said sheet passing under the fingers 39. The crank 34, of course, rotates constantly as the drum 2 is operated and the pitman 33 30 is thereby reciprocated. The supply of blotter or interleaving sheets is placed in the tray or magazine 18, as shown in Figure 6, the sheets being arranged in stepped relation. The gravitating holder and stop 35 37 bears with its plate 38 upon the uppermost sheet adjacent the rear end thereof and acts as a drag so that while the entire pile of sheets will be fed forward to a slight degree, the uppermost sheet will be drawn 40 from under the holder, as the pusher 19 moves forwardly whereupon the holder will drop onto the second sheet directly in rear of the top sheet, the feeding of more than one sheet at a time being thus avoided. 45 The forward movement of the pitman 33 obviously effects a forward movement of the pusher 19 which pushes the top sheet into the bight of the rolls 6 and 11, and, as the roll 6 rotates constantly, the sheet will 50 be at once engaged and fed forward onto the pins 39 which have been swung inwardly to receive it. On its return movement, the pusher will slide over the top sheet without imparting movement thereto, this result 55 being due to the inclined position of the pusher. The forward movement of the pitman also carries the tappet 50 against the crank pin 49 and thereby turns the rock shaft 47 so that the push rod 43 will be 60 forced inwardly thereby causing the fingers 65

39 to swing toward each other, as above described, to support the sheet issuing between the rolls 6 and 11. As the pitman moves rearwardly, the fingers will recede and drop the blotter sheet onto the printed sheet which, in the meanwhile, has been delivered into the receptacle. 70

It will be readily noted that my improved apparatus is simple and compact, may be applied to any duplicating machine without necessitating any substantial reorganization of the said machine, and may be operated efficiently at the same speed as the duplicating mechanism. 75

Having thus fully described my invention, 80 what I claim as new and desire to secure by Letters Patent of the United States is:—

1. The combination with a duplicating mechanism, and a receptacle for sheets delivered by said mechanism, of means for temporarily supporting an interleaving sheet over said receptacle, a magazine for the interleaving sheets, means for feeding sheets singly and successively from the magazine to the supporting means, and means for periodically operating the supporting means to deposit the interleaving sheets in the receptacle to interleave with the sheets delivered by the duplicating mechanism, said last mentioned means being operatively connected with and actuated by the duplicating mechanism. 85 90

2. The combination with a duplicating mechanism, and a receptacle for sheets delivered by said mechanism, of means for temporarily supporting an interleaving sheet over said receptacle, a magazine for the interleaving sheets, means for feeding sheets singly and successively from the magazine to the supporting means, and means for periodically operating the supporting means to deposit the interleaving sheets in the receptacle. 100 105

3. The combination with a duplicating mechanism, and a receptacle for sheets delivered by said mechanism, of means for temporarily supporting an interleaving sheet over the receptacle, a magazine for the interleaving sheets, means for feeding sheets singly and successively from the magazine to the supporting means, means to operate the supporting means whereby to deposit the supported sheet in the receptacle, and means in the magazine to maintain the sheets in stepped relation. 110 115

4. In interleaving apparatus, the combination of a receptacle, supporting fingers projecting over the receptacle, means for holding said fingers normally apart, and means for swinging said fingers toward each other to support a sheet. 120 125

5. In interleaving apparatus, the combination of a receptacle, supporting fingers projecting over the receptacle, rock shafts disposed in rear of the receptacle and carry- 130

ing said fingers, and means for simultaneously rocking said shafts in opposite directions whereby to cause the fingers to approach or recede.

5 6. In interleaving apparatus, the combination of supporting fingers, a push rod disposed transversely of the fingers, operative connections between the push rod and the fingers whereby to effect simultaneous move-

10 ment of the fingers in opposite directions, a vertically disposed rock shaft, a crank projecting radially from said shaft and pivoted to the push rod, and means for rocking said shaft.

15 7. In interleaving apparatus, the combination of supporting fingers, a push rod disposed transversely of the fingers, operative connections between the push rod and the fingers whereby to effect simultaneous move-

20 ment of the fingers in opposite directions, a vertically disposed rock shaft, a crank pro-

jecting radially from said shaft and pivoted to the push rod, a pitman reciprocating across the axial plane of said shaft, a second crank projecting from said shaft, and a tappet carried by said pitman and arranged to impinge against said second crank. 25

8. The combination of a duplicating mechanism, a receptacle in rear of said mechanism for printed sheets delivered by the same, a magazine in rear of the receptacle, and means for feeding sheets from the magazine into the receptacle to interleave with the sheets delivered by the duplicating 30 mechanism, said last-mentioned means being operatively connected with and actuated by the duplicating mechanism. 35

In testimony whereof I hereunto affix my signature.

JOHN J. EDWARDS.
